UNITED STATES PATENT OFFICE.

JOHN A. SECOR, OF LAPORTE, INDIANA, ASSIGNOR TO ADVANCE-RUMELY COMPANY, OF LAPORTE, INDIANA, A CORPORATION OF INDIANA.

PROCESS OF PREPARING AN EXPLOSIVE MIXTURE FOR INTERNAL-COMBUSTION ENGINES.

Application filed June 28, 1919. Serial No. 307,477.

To all whom it may concern:

Be it known that I, JOHN A. SECOR, a citizen of the United States, residing at Laporte, in the county of Laporte and State 5 of Indiana, have invented a certain new and useful Improvement in Processes of Preparing an Explosive Mixture for Internal-Combustion Engines, of which the following is a specification.

10 My invention relates to a process of producing a mixture of fuel and air for use in an internal combustion engine. In such engine are means for the incorporation of a mixture of the fuel ingredients and a passage for their subsequent transmission to the engine or cylinder. The mixture may consist of air and any kind of fuel, or air, fuel and water and the particular mixture with which I am concerned, is air, oil and 15 water. These ingredients are commonly united by some apparatus in the process of introduction so as to produce in effect a mixture consisting of air and atomized oil 20 and water. As these mixed ingredients pass along toward the cylinder, experience shows that a certain quantity of the fuel, oil or water or both tends to be separated out of the stream of the mixture by the impingement of the current on the walls of the 25 passageway or valves or controlling device which may be placed therein. My invention relates especially to compensating for this difficulty and it is illustrated by the 30 particular mechanism which may be used 35 to carry out my process. Of course, various other sorts of mechanisms could be devised, either automatically or hand controlled. The particular illustration which I have selected is that of an engine adapted to be 40 supplied with a mixture of oil, air and water and where the difficulties of separating out the liquids from the mixture current are due to the throttle valve.

In illustrating this:

45 Figure 1 is a cross section through the carburetor with a first reatomizing device;

Figure 2 is a detail cross section of the passage pipe with a modified form of atomizing device;

50 Figure 3 is a detail of an extension of the passageway and showing a reatomizer at the intake valve.

The device of Figure 3 is intended to be used in connection with the device of Fig-

ure 1 and the device of Figure 2; or any 55 other atomizing device could be substituted for either or both of the atomizing devices shown in Figures 1 and 3, but a single re-atomizing device of any kind could be used either near the throttle valve or near the intake valve or at any point between them.

Like parts are indicated by like characters throughout.

A is a part of the engine cylinder or housing containing the cylinder. A¹ is the carburetor casting which merely consists in an elongated tube flanged at A² so that the bolts A³ may attach it to the engine and provided with a water reservoir A⁴, fuel reservoir A⁵ and water nozzle A⁶ and fuel nozzle A⁷ discharging into the passage. A⁸ is a butterfly throttle valve between the fuel and water nozzles and the engine, adapted to be controlled by means of the lever A⁹ and link A¹⁰ from governor or other throttle 75 controlled mechanism not here specifically illustrated.

B is an atomizing or re-atomizing sleeve inserted in the passage immediately below the butterfly. This sleeve takes the form 80 of a modified Venturi tube. The modification consists in that the tube is cut away on the up-stream side of the point of greatest contraction so as to provide a sharp annular knife edge B¹ with a downwardly and 85 outwardly extending curved channel or reservoir B², the wall of the Venturi tube being sloped upwardly from the bottom of the reservoir as at B³ to finally merge into the normal Venturi contour. In order to 90 illustrate the slight modification the normal Venturi contour is shown in dotted lines as at B⁴.

The venturi B is integral with the flange C, and this flange may be inserted between 95 the carburetor and the engine, and the carburetor web will be protected against breaking by filler blocks C¹, or washers, which take the strain of the bolts, and are the same thickness as the flange C.

D is the engine intake valve carried on the valve stem D¹, controlled by means not here shown. It operates against a valve seat D² and this seat is made removable in the engine and carries, extending up toward 100 the carburetor, the Venturi tube D³ grooved or distorted at D⁴ in the same manner as the distortion of the member B. This ar-

angement gives a final atomization and mixing just as the mixture enters the engine, and thus we have a peculiarly homogeneous mixture which leads to peculiarly satisfactory operating results.

Thus I have disposed two Venturi tube atomizers between the throttle valve and the intake.

Referring to the device of Figure 2, the 10 passageway A¹ is provided with an interior trough F which is arranged about the side of the passageway and is provided with the edge G. Under certain conditions such a device might be operated more or less effectively to atomize the liquid by collecting it as it flows down the side and then exposing it to the outer knife like edge of the trough which lies in the path of the moving current of air or mixture. This is only done 15 to suggest the different forms of atomizer which might be employed.

The use and operation of my invention are as follows:—

The liquid fuel and the water, although, 25 of course, the water might be dispensed with, are fed into the carbureting pipes or chamber in the usual manner, being induced by the rapidly flowing air current caused by the operation of the engine. The means not 30 illustrated in detail, are provided, of course, for controlling the flow of both the liquid fuel and water. It will be noted that the water and fuel nozzles discharge into the carburetor at different points where the pressures 35 are different thus, of course, resulting in automatic differences at the nozzle which may be controlled and compensated for by manual adjustment of the needle valve.

The mixture then passes on through or 40 past the throttle valve. If the throttle valve is wide open and if the air velocities are high, there will be little change in the mixture, but as it passes through the Venturi tube, it will be re-atomized and re-mixed to 45 some certain extent.

If, however, the throttle is more or 50 less closed it will provide an obstruction against which the fuel will impinge, and, being heavier than the air, it will be separated out by inertia and the air will go on carrying probably a lean and unsatisfactory mixture and the liquid will run down the walls of the tube. This liquid will be caught 55 by the ledge in the venturi and the little annular reservoir formed by that ledge will be filled up with liquid, and as more liquid comes down, it will overflow the sharp knife edge. As it overflows, it comes into the direct path of the air and it will be suddenly 60 torn apart and atomized by such air.

Experience shows that the diameter of this modified Venturi tube for the lower re-atomizer must be a little larger to get the same capacity, than the diameter of a normal venturi. This is probably caused by

the fact that the effective diameter of the venturi is decreased by the thin film of oil overflowing the ledge all the way around, before this thin film of oil has time to be broken up and carried away as part of the 70 atomizing mixture.

I claim:

1. The process of forming an explosive mixture for internal combustion engines which consists in supplying liquid fuel to a 75 rapidly moving stream of air, controlling the flow of the mixture thus formed, and then re-atomizing any liquid particles that may have been thrown out of the column, and re-mixing the mixture, then conducting 80 the mixture toward the engine, and re-mixing it again immediately prior to its entrance into the combustion chamber.

2. The process of forming an explosive mixture for internal combustion engines 85 which consists in introducing to a rapidly moving confined current of air a quantity of a non-volatile hydro-carbon, segregating such part of said hydro-carbon as may be deposited from said current of air during 90 its movement and re-atomizing said part by means of said current of air without disturbing the general flow of said current of air.

3. The process of forming an explosive 95 mixture for internal combustion engines which consists in introducing to a rapidly moving confined current of air a quantity of a non-volatile hydro-carbon of high viscosity, segregating such part of said hydro-carbon 100 as may be deposited from said current of air during its movement and re-atomizing said part by means of said current of air while permitting the general flow of said current of air to continue undisturbed. 105

4. The process of forming an explosive mixture for internal combustion engines which consists in introducing to a rapidly moving confined current of air a quantity 110 of a non-volatile hydro-carbon of high viscosity, controlling the movement of said current of air, segregating such part of said hydro-carbon as may be deposited from said current of air during its movement and re-atomizing said part by means of said current 115 of air without disturbing the general flow of said current of air.

5. The process of forming an explosive mixture of a liquid hydro-carbon fuel which consists in introducing to a rapidly moving 120 confined current of air a quantity of said hydro-carbon, catching such part of said hydro-carbon as is deposited from said current during this movement and re-atomizing it into the current by means of the current of air without disturbing the general flow of the current.

6. The process of forming an explosive mixture of a non-volatile liquid hydro-carbon which consists in introducing to a 130

rapidly moving confined downward current of air a quantity of said hydro-carbon, controlling the flow of said current of air, catching such part of said hydro-carbon as 5 is deposited from said current during its movement and re-atomizing it into the current by means of the current of air without disturbing the general flow of the current.

In testimony whereof, I affix my signature in the presence of two witnesses this 10 24th day of June 1919.

JOHN A. SECOR.
